Primary Examiner—Jeffrey Asch

(74) Attorney, Agent, or Firm—Steven A. Shaw

(57) **CLAIM**

I claim the ornamental design for a key array for a handset, as shown and described.

DESCRIPTION

FIG. 1 is a front view of the key array for a handset; and, FIG. 2 is a perspective front view thereof.

The broken line showings of the handset are for illustrative purposes only and form no part of the claimed design.

1 Claim, 2 Drawing Sheets
